UNITED STATES PATENT OFFICE

2,202,290

FLIER FOR SPINNING MACHINES

Harvey E. Herr, Buffalo, N. Y., assignor to Herr Manufacturing Company, Inc., Buffalo, N. Y., a corporation of New York

Application January 24, 1939, Serial No. 252,691

5 Claims. (Cl. 57—116)

This invention relates to certain new and useful improvements in the fliers employed in connection with spinning machines and the like.

It has for one of its objects to provide a simple and efficient flier whose parts are so designed and constructed as to eliminate the use of lubricants and thereby prevent the threads being soiled during spinning.

Other features of the invention reside in the construction and arrangement of parts herein-after described and particularly pointed out in the appended claims.

In the accompanying drawing:

Figure 1 is a fragmentary front view of a portion of a spinning machine showing my improved flier applied thereto. Figure 2 is an enlarged top plan view of the flier and associated bobbin. Figure 3 is an enlarged fragmentary vertical section taken on line 3—3, Figure 2. Figure 4 is an enlarged horizontal section taken on line 4—4, Figure 3.

Similar characters of reference indicate corresponding parts throughout the several views.

This invention is applicable to spinning machines of well known construction, 10 indicating the bobbin-spindle and 11 the take-off bobbin mounted thereon. The thread or yarn from the bobbin extends upwardly through the eyes of the usual flier wires 12, 13 mounted on a holder or 20 wire-base 14, and thence is guided upwardly through a guide or centering eye 15 to a take-up spool (not shown).

The flier body to which the wire-base 14 is attached, is in the form of a self-contained unit 35 so designed that the use of lubricants is eliminated and the bearing member associated with the wire-base readily replaceable when worn out without disturbing the rest of the flier body. This flier body consists of a split expandable anchoring sleeve 16 adapted for frictional engagement with the tapered end of the spindle 10, a journal member 17 disposed about the sleeve for rotation relative thereto, and a bearing member 18 rotatably mounted on the journal member and to 45 which the wire-base 14 is attached. Intermediate its upper and lower ends the sleeve 16 has an external flange or thrust shoulder 19 and the journal member is provided at its lower end with an internal socket 20 about the thrust shoulder 50 for limiting the axial displacement of the journal member. As shown in Figure 3, this socket may be formed by providing the lower end of the journal member with a flange 21 and attaching to this flange a cup-like member 22. The sleeve and 55 journal member 17 are preferably made of metal,

while the bearing member 18 to which the wire-base is attached, is preferably made of fiber or like material.

The bearing member 18 is more or less freely mounted on the journal member, being detachably retained against limited axial displacement at one end by a shoulder 23 formed adjacent the lower end of the journal member, while the upper end of the latter has a detachable, split band 24 forming a shoulder for limiting the upward displacement of the bearing member. When applying or removing the bearing member, the split band 24 is removed from the journal member.

While manifestly simple in construction, this improved flier renders the use of lubricants unnecessary and thereby prevents soiling of the threads, and furthermore it enables the ready replacement of the fiber bearing member when worn, thereby reducing the maintenance costs of the fliers to a minimum.

I claim as my invention:

1. A flier for spinning machines and the like, comprising a split expandable sleeve adapted for attachment to a bobbin-spindle, a journal member disposed in spaced relation about said sleeve for rotation relative thereto, complementary means on the outer and inner faces of said sleeve and said journal member, respectively, for holding the latter against limited axial displacement relative to the former, a bearing member detachably mounted on said journal member, and a wire base attached to said bearing member.

2. A flier for spinning machines and the like, comprising an expandable sleeve adapted for attachment to a bobbin-spindle, a metal journal member disposed in spaced relation about said sleeve for rotation relative thereto complementary external and internal means on said sleeve and said journal member, respectively, for holding the latter against limited axial displacement relative to the former, and a fiber bearing member mounted on said journal member and having a wire-base borne thereby.

3. A flier for spinning machines and the like, comprising a split, expandable sleeve adapted for attachment to a bobbin-spindle and having a thrust shoulder thereon, a journal member mounted on the sleeve for limited axial displacement relative thereto and having a socket therein into which said thrust shoulder freely extends, and a bearing member detachably mounted on said journal member and having a wire base borne thereby.

4. A flier for spinning machines and the like, comprising a split, expandable sleeve adapted for

attachment to a bobbin-spindle and having a thrust shoulder thereon, a journal member mounted on the sleeve for limited axial displacement relative thereto and having a socket therein into which said thrust shoulder freely extends, said journal member having a fixed bearing shoulder adjacent one end thereof and a detachable bearing shoulder adjacent its opposite end, and a bearing member having a wire base thereon 10 detachably mounted on said journal member between its bearing shoulders.

5. A flier for spinning machines and the like, comprising a split, expansible sleeve adapted for attachment to a bobbin-spindle and having an

external thrust shoulder thereon intermediate its ends, a metallic journal member mounted on the sleeve for limited axial displacement relative thereto and having an internal socket therein about said thrust shoulder and an external bearing shoulder adjacent the lower end thereof, a detachable bearing shoulder applied to the upper end of said journal member, a fiber bearing member detachably mounted on the journal member for limited axial displacement between the bearing shoulders thereof, and a wire base attached to said bearing member. 5 10
